CONSTRUCTION OF A FASCIA GUTTER

David J. Brown, Olivers Battery, England, assignor to Conder International Limited, Winchester, Hampshire,
England, a company of Great Britain

Filed Nov. 4, 1968, Ser. No. 14,305

Claims priority, application Great Britain May 9, 1968

Term of patent 14 years

Int. Cl. D23—01

U.S. Cl. D23—45

FIG. 2

FIG. 1 is a perspective view of a gutter showing my new design, a center portion being broken away to indicate indeterminate length; and

FIG. 2 is a transverse cross-sectional view thereof.

I claim:

The ornamental design for a construction of a fascia gutter, as shown.
